(57) CLAIM

The ornamental design for jeans, as shown and described.

DESCRIPTION

FIG. 1 is a front perspective view of jeans showing our new design;

FIG. 2 is a front elevational view thereof;

FIG. 3 is a rear elevational view thereof;

FIG. 4 is a left side elevational view thereof, the undisclosed right side elevational view being a mirror image thereof;

FIG. 5 is a top plan view thereof; and,

FIG. 6 is a bottom plan view thereof.

The broken lines showing fabric patterns in the figures are included for the purpose of illustrating contrasting color regions in the jeans, and form no part of the claimed design.
